UNITED STATES PATENT OFFICE.

WILLIAM R. THOMAS, OF WATERTOWN, WISCONSIN, ASSIGNOR OF ONE-HALF TO
JOHN MURPHY, OF WATERTOWN, WISCONSIN.

ROAD TAMPER.

Application filed May 8, 1922. Serial No. 559,352.

To all whom it may concern:

Be it known that I, WILLIAM R. THOMAS, a citizen of the United States, and resident of Watertown, in the county of Jefferson 5 and State of Wisconsin, have invented certain new and useful Improvements in Road Tamers; and I do hereby declare that the following is a full, clear, and exact description thereof.

10 The invention relates to road tamers adapted to be propelled by tractors. It comprises a frame affixed to a tractor, and transmitting power therefrom to a rock shaft carrying rocking arms, some disposed forwardly, others rearwardly, and having tamers thereon, adapted to contact with the ground. The rocking arms and tamers counter-balance each other. A grader is provided with means for regulating its 20 height, the grader being carried in front of the tamers.

A primary object of the invention is effective tamping action. Power is transmitted from the tractor, and the counter-balanced arrangement of rocking arms on the rock shaft facilitates a raising and lowering of the tamers with a minimum expenditure of energy, as the movement upward of the forward series of tamers is simultaneous 30 with the lowering of the rearward series. The movement of the rocking arms is such as to impart a proper tamping force to the tamers. The tamers pivoted on the rocking arms operate with but little shock to the frame, as the sudden arrest of the tamers does not transmit excessive force to the rocking arms.

An additional object is the convenient propulsion of the tamers, the tamper frame 40 being secured to the front of a tractor and provided with wheels whereby it may be pushed about, offering but the minimum resistance to movement.

A still further object of the invention 45 is the provision of devices regulable to determine the position of the grader, so that the surface on which the tamers act is at a proper height for efficient work.

With the above and other objects in view 50 which will appear as the description proceeds, the invention resides in the novel construction, combination and arrangement of parts substantially as hereinafter described and more particularly defined by the appended claims, it being understood that such

changes in the precise embodiment of the herein disclosed invention may be made as come within the scope of the claims.

In the accompanying drawing, is illustrated one complete example of the physical 60 embodiment of the present invention constructed according to the best mode so far devised for the practical application of the principles thereof, and in which:

Figure 1 is a longitudinal sectional view 65 of the device.

Figure 2 is a plan thereof, parts being shown in section.

Figure 3 is a cross section on the line 3—3 70 of Figure 1.

Figures 4 and 5 are details of a specific modification of tamper, the latter being a cross section on the line 5—5 of Figure 4.

Figures 6 and 7 are details of a catch, Figure 6 being a cross sectional view on the line 75 6—6 of Figure 7.

The top frame comprises longitudinal members 10—10', terminating in transverse members 11—11'. The side frames comprise diagonal supports 12 and 13, which at their forward ends are secured to vertical front frame members 14, and at their rear ends are rigid with vertical rear frame end members 15.

Between vertical end frame members 15, 85 are vertical supports 16 and the end members and supports are rigid with transverse top frame member 11' and transverse bottom frame member 17 at the rear. Side bottom frame members 18 extend from transverse bottom frame member 17 forwardly to front transverse member 19. Side bottom frame members 18 are braced by transverse brace 20, which is rigid with longitudinal braces 21, extending to front transverse 90 member 19. The bottom frame carries a plurality of lugs 22, having openings receiving rod 23, which is secured to a tractor by means of suitable propelling elements 24, the top frame being provided with ears 25, by 100 which the structure may be secured to the tractor thru the medium of chains 26 at each of the rear corners.

Brace 20 carries supports 27, upwardly extending and having bearings 28 thereon for shaft 29, rigid with wheels 30 and gear 31, the gear operating to transmit power thru suitable connection not shown from a tractor to shaft 29, on the rotation of which reciprocates pitman 31', pivoted on wheels 110

30 and connected to depending lugs 32, carried by rocking arms 33, secured to rock shaft 34, mounted to rotate on vertical front frame members 14. Rocking arms 33 are 5 forwardly disposed and are the extremes of a series of forwardly disposed members comprising rocking arms 35, and a series of rearwardly disposed rocking arms 36, the arms being secured to rock shaft 34 10 by bolts 37. Each of the rocking arms is provided with bifurcations 38, between which a lever 39 is mounted on pivot 40, the bifurcations having a lower stop 41, and an upper stop 42, limiting the rotation 15 of lever 39 in one direction.

Stop 42 is provided with a plurality of grooves 43, in one of which a U-bolt 44 is positioned, secured at its lowermost end to link 45, which supports helical spring 20 46, which contacts with the arm of lever 39, terminating adjacent rock shaft 34, to each of the levers.

A link 47 is provided, the link being pivoted at its lower end to tamper 48, and 25 having a band 49 secured thereto by pin 50, whereby leaf springs 51 oppositely disposed are maintained in contact with the upper surface of tamper 48. If, in the downward movement of the tamper, its 30 lower surface is in a different plane from that of the ground on which the tamper acts, the pivotal movement of the tamper permits readjustment, so that the tamper exerts a depressing action in the proper 35 direction. Springs 51 tend to maintain the tamper in proper position in spite of vibration of the frame and movement of other parts to bring the lower surface of the tamper into a substantially horizontal 40 plane. The rocking of shaft 34 by pitman 31', moves the forward rocking arms up and down, the rearward rocking arms traveling in an opposite direction so that weight of the tamping parts counter balance, thus 45 less force is necessary for the tamping action than would be called for if all the rocking arms were disposed in the same direction with respect to shaft 34.

When the tamper 48 contacts with the 50 ground, the rocking arm on which the tamper is mounted is capable of continued downward movement under the influence of pitman 31', and spring 46 acting on lever 39, produces a heavy depression of the tamper. As lever 39 is pivoted to the rocking arm, the shock of impact of tamper 55 48 with the ground is not communicated to the frame. U-bolt 44 may be positioned forwardly or rearwardly in grooves 43, and thus is effective to vary the tension of spring 46.

In the modification shown in Figures 4 and 5, rock shaft 52 carries rocking arm 53, secured by bolt 54 and having a stop 60 55 adapted to limit the movement of arm

56 of a trip rotating on pivot 57, the arm being normally maintained uplifted by leaf spring 58, secured to the rocking arm. On the upward movement of the rocking arm, finger 59 contacts with frame piece 60, depressing arm 56 bringing it out of contact with the end of lever 61 pivoted on the rocking arm. This permits the dropping of the tamper 48'. Thus the tamper is elevated to a proper height and released, and by its sudden impact with the ground, produces an effective tamping action. 75

Pivoted to vertical front frame members 14, are a series of forwardly extending arms 62, carrying a grader 63, provided with 80 lugs 64, to which is pivoted a series of rack bars 65, the teeth of which mesh with gears 66, rigid with shaft 67, which is manually rotatable by means of wheel 68, to determine the position of rack bars 65 and thus regulate the height of grader 63, the shaft 67 being mounted to rotate in supports 69. Thus by wheel 68, the level of the surface on which tampers 48 act may, to a certain extent, be determined and the ground is leveled by the grader so that the tampers 85 48 are disposed at a proper height for pounding the material down.

On the adjustment of grader 63 to a proper height, lever 70, rotatable on pivot 95 71, is moved laterally to shift a traveler 72, slidably mounted on shaft 67 and bring catches 73, extending parallel to the axis of the shaft into engagement with the teeth of gear 66, movement being transmitted 100 from lever 70 to traveler 72, by means of pins 74, rigid with the traveler and movable in slot 75 in the lever. By means of the lever 70, therefore, rack bars 65 are retained in fixed position. As the wheels 76 mounted to rotate at the lower front corners of the frame are positioned almost immediately below the rocking shaft 34, the forward and rearward tampers 48 are maintained 105 at substantially equal heights above the ground, despite irregularities so that all of the tampers are effective. If desired, a suitable source of power may be carried in the frame and operate directly to move the tampers instead of furnishing the power 110 from the tractor. 115

I claim:

1. A road tamping machine adapted to be drawn over a roadway comprising a wheeled frame, a rock shaft extending transversely of said frame, a plurality of levers projecting forwardly and rearwardly of said rock shaft and rigidly attached thereto, means for oscillating said rock shaft, each of said levers being composite and having an outer portion and an inner portion with the outer portion pivoted intermediate its ends to the inner portion, a spring carried by said inner portion and opposing rocking motion in one direction of said outer por- 120 125 130

tion, and a tamper suspended from said outer portion.

2. A road tamping machine adapted to be drawn over a roadway comprising a wheeled frame, a rock shaft extending transversely of said frame, a plurality of levers projecting forwardly and rearwardly of said rock shaft and rigidly attached thereto, means for oscillating said rock shaft, 10 each of said levers being composite and having an outer portion and an inner portion with the outer portion pivoted intermediate its ends to the inner portion, a spring carried by said inner portion and 15 opposing rocking motion in one direction of said outer portion, and a tamper suspended from said outer portion, said tamper having a downwardly extending link and having a foot portion pivoted to said link 20 and resiliently held at approximately right angles thereto.

3. A road tamping machine comprising a wheeled vehicle adapted to be drawn over a roadway, a transverse shaft carried by

said vehicle, means for oscillating said shaft, 25 a plurality of levers projecting forwardly and rearwardly in staggered relation from said transverse shaft, and a plurality of tampers carried by the outer ends of said levers. 30

4. The combination of a road tamping machine adapted to be drawn over a roadway and comprising a frame, supporting wheels therefor, a transverse shaft carried by said frame, means for rocking said shaft, a plurality of forwardly and rearwardly projecting levers rigidly attached to said shaft, a plurality of tampers suspended from the outer ends of said levers and having movable feet, and a scraper carried by said 35 frame and adjustably mounted thereon and adapted to control the height of material presented to said tampers. 40

In testimony that I claim the foregoing I have hereunto set my hand at Watertown, 45 in the county of Jefferson and State of Wisconsin.

WILLIAM R. THOMAS.
